MANICURING CASE

Richard B. Hall, Cincinnati, Ohio, assignor to Dominion
Electric Corporation, a corporation of Ohio

Filed Mar. 8, 1963, Ser. No. 73,898

Term of patent 14 years

(Cl. D86—10)

FIG. 1

FIG. 2

FIG. 3

FIG. 4

FIG. 5

FIGURE 1 is a front perspective view of a manicuring case showing my new design as it appears in closed position;

FIGURE 4 is a front perspective view as it appears with the cover swung up to open position;

I claim:

The ornamental design for a manicuring case, substantially as shown.
